UNITED STATES PATENT OFFICE.

JOHN T. WIGLEY, OF SYRACUSE, NEW YORK.

DESIGN FOR A PLATE.

44,505.

Specification for Design.

Patented Aug. 12, 1913.

Application filed June 27, 1913. Serial No. 776,178. Term of patent 7 years.

To all whom it may concern:

Be it known that I, JOHN T. WIGLEY, a citizen of the United States, residing in Syracuse, county of Onondaga, and State of New York, have invented a new, original, and ornamental Design for a Plate, of which the following is a specification, reference being had to the accompanying drawing, forming a part thereof.

The figure is a plan view of a plate, showing my new design.

I claim:

The ornamental design for a plate as shown.

JOHN T. WIGLEY.

Witnesses:

JNO. B. TUCK,
ELLEN M. SMITH.
